Primary Examiner — Robert M. Spear(74) *Attorney, Agent, or Firm* — Laurence A. Greenberg; Werner H. Stemer; Ralph E. Locher(57) **CLAIM**

The ornamental design for a tire, as shown and described.

DESCRIPTION

FIG. 1 is a front perspective view of the tire showing my new invention;

FIG. 2 is a front elevation view thereof;

FIG. 3 is a enlarged partial front elevation view thereof;

FIG. 4 is a left side elevation view thereof; and,

FIG. 5 is a right side elevation view thereof.

The broken lines depict the border between the claimed tire and the unclaimed interior of the tire and represents no part of the claimed design.
